CLAIM

The ornamental design for a mixed reality eyeglasses or a portion thereof with an animated graphical user interface, as shown and described.

DESCRIPTION

FIG. 1 is a front view of a mixed reality eyeglasses or a portion thereof with a first image of an animated graphical user interface showing our new design; FIG. 2 is a second image thereof; and, FIG. 3 is a third image thereof.

The appearance of an image sequentially transitions to another between FIGS. 1-3. The process or period in which an image transitions to another forms no part of the claimed design.

The outermost broken lines illustrating unclaimed portions of a mixed reality eyeglasses or a portion thereof with animated graphical user interface form no part of the claimed design. The other broken lines illustrating unclaimed portion of an animated graphical user interface form no part of the claimed design.
